UNITED STATES PATENT OFFICE.

GEORGE E. WARING, JR., OF NEWPORT, RHODE ISLAND, ASSIGNOR TO THE DRAINAGE CONSTRUCTION COMPANY, OF BOSTON, MASSACHUSETTS.

SEWER-CLEANING APPLIANCE.

SPECIFICATION forming part of Letters Patent No. 623,585, dated April 25, 1899.

Application filed February 15, 1893. Serial No. 462,465. (No model.)

To all whom it may concern:

Be it known that I, GEORGE E. WARING, Jr., of the city and county of Newport, in the State of Rhode Island, have made a new and useful Improvement in Sewer-Cleaning Appliances, of which the following is a specification.

All sewers are more or less liable to obstruction and some provision must be made for the removal of such obstructions when they occur. The earlier sewers were as a rule of such a size as to make it necessary that workmen should enter them from time to time to clean them out. Access to the sewers for this purpose was provided by means of manholes. The manhole as applied to the more modern system of small pipe-sewers is a costly survival of the condition which made its former use imperative. It is of course of no value as a means for longitudinal inspection of a small pipe-sewer for any distance, and it is only useful as a means by which tools may be inserted into a sewer. The tools are attached to and manipulated by sectional rods or pipes or are carried by ropes drawn through from one manhole to another. In this manner a certain amount of force is brought to bear upon an obstruction or deposits are so disturbed as to lead to their being washed away by a strong current. The most certain and effective method of applying such force at any given distant point in a sewer is by means of a column of water reaching from the point of operation to the obstacle and filling this portion of the sewer completely. As the water is incompressible, pressure upon the forcing-tool at one end of the column is transmitted to the point of obstruction as effectively as through a solid rod. The most complete and effective method of removing deposits from a sewer is by means of a vigorous agitation of water submerging them, followed by a strong flushing-current that will sweep away the material of which the deposit was formed.

The purpose of my invention, among other things, is to provide a simple and inexpensive means whereby direct force or pressure can be applied to obstructions or an agitating or rinsing effect to deposits through a column of water. This I do by providing

suitable openings at various points in the course of the sewer adapted for the introduction of sewer force-pumps and their appurtenances, all as hereinafter set forth.

55

The details of construction are shown in the drawings, in which—

Figure 1 is a sectional view showing a portion of a sewer and two inspection or cleaning pipes, with a sewer force-pump in each, as applied in producing an agitation of the included column of water for the stirring up of deposits. Fig. 2 shows the pump-cylinder and dam. Fig. 3 is an isometric view of the pump or dam socket A. Fig. 4 is a plan of the same. Fig. 5 is a section of the inspection-hole cover. Fig. 6 is a plan of the same. Fig. 7 is a plan, on an enlarged scale, of the guide C; and Fig. 8, an elevation, on an enlarged scale, showing the details of one of its 70 points of support.

The pump or dam socket A is a block, preferably of concrete or similar material, perforated in a horizontal direction with a channel corresponding with that of the sewer of which it forms a part. At its top is a vertical opening, preferably of the same diameter as the sewer-channel, from which a channel D, as of vitrified pipe, is carried to the surface of the ground, with a suitably-arranged case 80 and cover at the top—as, for example, the case H and cover G.

The pump-cylinder E is a tube, preferably of heavy brass, with an external diameter corresponding with the vertical opening in the top of the block A, through which it passes and on which it is supported by the rim K, which serves to hold the tube in its proper relation to the sewer-channel below. The lower end of the pump-cylinder E is cut to fit the section of the sewer-channel, and when in place constitutes a dam B. This dam may be made independently, if preferred, in any way that will stop the flow of the sewer.

e is a piston, which preferably fits the pump-cylinder E as tightly as smooth working will allow. If desired, it may be made to fit more loosely in the channel D, producing its effect of transmitting motion to the water column F by a reciprocating motion in the channel 100 in rhythm with the undulation of the water column. This water column is formed by an

accumulation of the flow of the sewer or in case of complete stoppage by filling the sewer between the points of obstruction and operation and so much of the pump-cylinder 5 E or channel D as will allow the proper effect of the piston e.

L is a bushing to be inserted in the upper end of the pump-cylinder E to prevent the unintentional withdrawal of the piston e and 10 to furnish a means for the removal of the pump and dam when desired by a continued raising of the piston-rod. It may be held in place by a screw-thread, as shown, and may be provided with the holes lll for the reception 15 of a tool, by which it may be screwed into or out of position.

C is a guide designed to hold the pump-cylinder E and the piston-rod e' concentric with each other and with the channel D and 20 to furnish a certain amount of frictional resistance against the unintentional withdrawal of the pump-cylinder E and dam B. It is made, preferably, with three arms, each somewhat shorter than the radius of the channel 25 D, with their ends c c c provided with loops of rubber or similar elastic material that will fit the channel D snugly, taking a frictional hold upon its walls. The lower side of each of the ends c c c is furnished with a wedge-shaped lug, as shown, for the purpose of centering and securing the bushing L and consequently the pump-cylinder E. It is provided with a circular opening S, through which the piston-rod passes.

30 H is an annular case of cast-iron or similar material designed to continue the channel D to the surface of the ground and to support the cover G. It is provided with pins h h, projecting from its sides, designed to engage 35 in the slots g' g' of the cover G as it is applied and lock it in place. The slots g' g' in the rim g of the cover G consist each of two secondary vertical slots connected by a short horizontal slot, as shown. The object of this 40 particular form of slot is to provide in connection with the pins h h a means whereby the lifting of the cover G to any considerable extent may be prevented, as also the turning and consequent unlocking thereof resulting 45 from a glancing blow or oblique pressure near its periphery, as from the hoof of a horse. The surface of the cover G may be provided with suitable notches or holes to receive the lifting-tongs, which may also be used to turn 50 the cover horizontally in engaging or disengaging the locking device.

The operation of my invention is as follows: For purposes of inspection it is only necessary to unlock and remove the cover G and 55 look down the channel D, as into an ordinary lamp-hole. In case of obstruction the opening immediately below the obstruction is uncovered, and a pump and dam E B (of which but a very few will be needed in any one community) are inserted, with the dam on the downstream side of the vertical opening in the pump-socket A and secured in place by

the guide C, the piston e being already in the cylinder. If the obstruction is not water-tight, the dam will cause the flow of the sewer to 70 accumulate and back up to a point beyond the obstruction. If the obstruction is of such a nature as to allow no sewage to pass it, the water column F can be formed by introducing water through the pump-cylinder E, the 75 bushing L and piston e having been first removed. When the water column lies solidly against the obstruction, the piston e and bushing L are replaced, and any desired force is brought to bear upon the obstacle by depressing the piston e. As soon as the obstruction yields, and its yielding will be felt at the piston, the pump and dam are withdrawn, and the retained water, acting as a strong flushing-stream, carries the obstructing materials 80 on to the outlet. By this means pressure can be brought to bear upon an obstruction from below, giving a backward push to the obstructing material and often releasing it from its entanglement when pressure applied from 85 above might only serve to increase the difficulty and compact the obstruction. In the case of deposit, which does not, however, amount to obstruction, a reciprocating motion of the piston e will cause an agitation of the 90 water column F, stirring up the deposit, which will be swept away by the release of the water before it has had time to settle again. If it is desired to give a more positive motion to the water column F, two pumps may be employed, one above and one below the deposit, as shown in Fig. 1, working in opposite directions, but in rhythm. If it is desired to cleanse the sewer by passing a ball through it, the ball can be inserted at any one of the 95 inspection-holes and can be caught and withdrawn at any other in the course of the sewer by a suitable basket or cage inserted instead of the dam B.

I am aware that oblique inspection-pipes 100 have been used for the purpose of aiding the removal of deposits. Although allowing a considerable agitation of the water by the use of a loose plunger, this device does not and cannot be made conveniently to operate 105 as a force-pump for the removal of obstructions and deposits. The oblique position of the pipes and the difficulty of making a good foundation for the street-chamber in which they end is found in practice to make them 110 liable to be broken or distorted by settlement. The oblique position of the pipes makes it necessary to resort to artificial illumination when it is desired to inspect the flow of the sewers with which they are connected. In 115 order to perform cleaning operations in both directions, it is necessary that two pipes be provided, one directed up, and the other down stream. Their cost is great. The above-described disadvantages attending the use of 120 oblique inspection-pipes are obviated by the use of the device of my invention.

What I claim as new, and desire to secure by Letters Patent, is—

1. In combination with a channel for the flow of liquid, the pump E, with an extension of one of its sides, constituting the dam B, opening at its other side into the said channel, as and for the purpose described.
2. In combination with a covered conduit for the flow of liquids, the socket A and the pump E, the latter fitting the vertical opening in the said socket, and having one of its sides extended into a dam B, as and for the purpose set forth.
3. In combination with a covered conduit containing flowing liquid, mechanism for the cleansing of the said conduit or the removal of obstructions therefrom, consisting of a pipe 15 or block, laid in the course of and forming a part of the said conduit and provided with an opening into the said conduit, a dam or plug closing the conduit below the said opening and holding back the flowing liquid, and 20 means for imparting motion to the resultant column of water formed above the said opening, substantially as described.
